CLAIM

The ornamental design for a snow fence for membrane pad, as shown and described.

DESCRIPTION

FIG. 1 is a perspective of the snow fence for membrane pad in accordance with the present invention;

FIG. 2 is a front view of the snow fence for membrane pad;

FIG. 3 is a back view of the snow fence for membrane pad;

FIG. 4 is a right side view of the snow fence for membrane pad;

FIG. 5 is a left side view of the snow fence for membrane pad;

FIG. 6 is a top view of snow fence for membrane pad; and, FIG. 7 is a bottom view of the snow fence for membrane pad.

The broken lines in the disclosure of FIGS. 1-7 is understood to be for illustrative purposes and forms no part of the claimed design.

1 Claim, 7 Drawing Sheets
